(57) **CLAIM**

The ornamental design for a container holder for liquid dispensing, as shown and described.

DESCRIPTION

FIG. 1 is a perspective view of the design;
 FIG. 2 is a first elevation view thereof;
 FIG. 3 is a second elevation view thereof;
 FIG. 4 is a third elevational view thereof;
 FIG. 5 is a fourth elevational view thereof;
 FIG. 6 is a top plan view thereof; and,
 FIG. 7 is a bottom plan view thereof.

The broken lines depict portions of the container holder for liquid dispensing that form no part of the claimed design.
